UNITED STATES PATENT OFFICE.

ALBERT F. BRAUN, OF CLAY CENTER, KANSAS.

PIPE-PULLER.

1,305,438.

Specification of Letters Patent. Patented June 3, 1919.

Application filed August 9, 1918. Serial No. 249,202.

To all whom it may concern:

Be it known that I, ALBERT F. BRAUN, a citizen of the United States, residing at Clay Center, in the county of Clay, State of Kansas, have invented certain new and useful Improvements in Pipe-Pullers; and I do hereby declare the following to be a full, clear, and exact description of the invention, such as will enable others skilled in the art 10 to which it appertains to make and use the same.

This invention relates to improvements in pipe pullers and particularly to devices for regaining pump pipes which have fallen or 15 dropped down into the well casings or tubes.

One object of the present invention is to provide a novel and improved device of this character whereby the fallen pipe can be easily and quickly reached and grasped for 20 the purpose of pulling the same upwardly out of the tubing.

Another object of the invention is to provide a novel and improved device of this character which includes an efficient means 25 for passage downwardly within the well tubing and over the pipe for the purpose of getting a firm grip on the pipe.

Other objects and advantages will be apparent from the following description when 30 taken in connection with the accompanying drawing.

In the drawing:

Figure 1 is a vertical sectional view through a portion of a well tubing, showing 35 the fallen pipe therein, and the invention about to engage therewith.

Fig. 2 is a vertical sectional view through the invention and the well tubing showing the pipe properly disposed through the 40 invention and gripped by the dog.

Fig. 3 is a vertical longitudinal sectional view taken on a line which extends through a plane at right angles to that of Fig. 2.

Fig. 4 is a horizontal sectional view taken 45 on the line 4—4 of Fig. 1.

Referring particularly to the accompanying drawing, 10 represents the well tubing, and 11 the fallen pump pipe which is to be lifted by means of the present invention.

The present invention includes a truncated 50 cone-shaped member 12, which is hollow, and open at both ends, as clearly shown in the drawing. Secured around the upper or

smaller end of the member 12 is a collar 13, the same being cut out, on one side to form 55 a longitudinal elongated opening 14, at each side of which is formed an apertured lug 15. Through the opening 14 is disposed the dog 16 which is pivotally mounted between said lugs 15. This dog extends into the collar to 60 a distance which permits it to bear against the pipe 11, when the cone member has been lowered to such a point as to permit the said pipe to pass upwardly through the upper end of the cone member. Secured to the 65 upper end of the collar 13 is a coupling member 17 which receives the lower end of the lifting pipe or rod section 18, by means of which the device is lowered into and lifted from the tubing 10. Secured within the upper portion of the cone member is a stop member 19 which is engaged by the inner portion of the dog to limit the downward movement thereof. A coil spring 20 is secured to the inner portion of the dog and to 70 the collar to hold the dog yieldably against the stop member. 75

The openings 15' of the lugs 15 are arranged in longitudinally extending oblique lines and are arranged to receive the pivot 80 of the dog, so that the dog is capable of adjustment to bring the same closer to or farther away from the pipe to be gripped, thus enabling the dog to grip pipes of different diameters. 85

In the operation of the device, the cone member is let down into the well tubing, as shown in Figs. 1 and 2 of the drawing, until the upper end of the pipe is disposed within the larger end of the cone. It will be noted that the mouth of the cone member is beveled to facilitate the engagement of and positioning of the pipe therein, as shown at 12'. Then, upon pushing the cone member downwardly, the pipe 11 will be passed upwardly 90 into engagement with the dog, which dog will firmly press the pipe against the other side of the inner face of the collar, whereupon the device will draw the pipe 11 from the tubing 10, when lifted upwardly. 95

What is claimed is:

A pipe puller for a well, including a hollow cone member, means for manipulating the cone member within the well to engage the end of the pipe therein, a collar 105 secured around the upper end of the cone

member and having an opening in one side, parallel wings formed on the collar at the sides of the opening, said wings being formed with longitudinally extending and 5 transversely alining series of openings, a stop member mounted in the upper end of the cone member, and a spring pressed pawl mounted on a pivot which is adjustable with

respect to said openings, and moving through said opening.

10

In testimony whereof, I affix my signature, in the presence of two witnesses.

ALBERT F. BRAUN.
